UNITED STATES PATENT OFFICE.

JOHN ZULICH, OF CLEVELAND, OHIO, ASSIGNOR OF FORTY-NINE ONE-HUNDREDTHS
TO CARL W. SCHAEFER, OF LAKEWOOD, OHIO.

CASING FOR LAMINATED SPRINGS.

Application filed March 8, 1922. Serial No. 541,919.

To all whom it may concern:

Be it known that I, JOHN ZULICH, a citizen of the United States, residing at Cleveland, in the county of Cuyahoga and State of Ohio, have invented a new and useful Casing for Laminated Springs, of which the following is a specification.

This invention relates to improvements in protective and lubricating flexible casings for laminated springs, and pertains more especially to a flexible metal casing extending longitudinally of and adapted to flex with a laminated spring which is reduced in thickness toward one end and adapted to be connected at said end to a vehicle-body or object in the support and cushioning of which the spring is to participate.

One object of this invention is to produce a highly practical casing of the character indicated which extends longitudinally of the spring and comprises a flexible strip spirally wound or coiled a suitable number of times around the spring in the direction of the thickest portion of the spring from a point adjacent the aforesaid end of the spring and held against unwinding.

Another object is to produce a strong, durable, inexpensive and attractive metal casing of the character indicated which is adapted to expand or contract endwise of the spring as may be required during flexing of the spring and facilitated and insures adequate lubrication of the leaves of the spring.

With these objects in view, and to attain any other object hereinafter appearing, this invention consists in certain features of construction, and combinations and relative arrangements of parts, hereinafter described in this specification pointed out in the claims, and illustrated in the accompanying drawings.

Referring to said drawings, Figure 1 is a plan view of a flexible sheet-metal strip employed in making a casing embodying my invention, and the central portion of said strip is shown broken away to reduce the size of the drawing. Fig. 2 is a cross-section taken along the line 2-2 in Fig. 1. Fig. 3 is a side elevation of a laminated spring provided with a flexible casing embodying my invention and shows the spring mounted on a spring-supporting axle or member which is shown in cross-section. Fig. 4 is a side view of the free end portion

of the spring and spring-surrounding casing shown in Fig. 3. Fig. 5 is a top plan in relation to Fig. 4, and a portion is broken away in Fig. 5 to more clearly show the construction. Fig. 6 is a longitudinal vertical section taken along the line 6-6 in Fig. 5. Fig. 7 is a transverse vertical section taken along the line 7-7 in Fig. 3. Fig. 8 is a section taken along the line 8-8 in Fig. 6. Fig. 9 is a vertical section taken along the line 9-9 in Fig. 7. Figs. 4, 5, 6, 7, 8 and 9 are drawn on a larger scale than Figs. 1, 2 and 3.

Figs. 1 and 2 of said drawings show a thin flexible sheet-metal strip 12 employed in making my improved casing for a laminated spring, and in Fig. 3 is shown a vehicle-axle or member 13 on which is mounted a laminated spring comprising several superposed leaves 14 extending longitudinally of the spring. Said spring is shown as overlapping the top of the spring-supporting member 13 and secured to said member 13 in any approved manner, as, for instance, by a suitably applied clip comprising a top plate 15 mounted on the spring and bolts 16 and nuts 17 by which the spring is caused to be clamped by and between said plate and said spring-supporting member. The construction and application of a spring-securing clip are too well known in the art to require further description and illustration in this specification. Suffice it to state that said spring is rigid with the supporting member 13 and projects laterally of said supporting member in one direction and has a vertically movable or free end which is spaced in said direction from said supporting member, that the upper of adjacent leaves of the spring projects farther in said direction than the lower of said leaves, and that the spring is therefore reduced in size or thickness vertically in the direction of its aforesaid free end.

The uppermost leaf of the illustrated spring is shown terminating, at said end of the spring, in a horizontally arranged tubular member or eye 18 at which the spring is adapted to be connected to a vehicle-body or object (not shown) in the support and cushioning of which the spring is to participate.

The strip 12 shown in Figs. 1 and 2 is preferably sold wound on a spool (not shown) and, when needed for the formation

- 2
- of a casing for a laminated spring, is unwound from the spool and then spirally wound or coiled several times around the spring, as shown in Fig. 3, in the direction 5 of the axle-overlapping or fixed and thickest portion of the spring from a point adjacent the hereinbefore mentioned free end of the spring and held against unwinding from the spring as will hereinafter appear.
- 10 The strip 12 has two parallel outwardly projecting offset portions 20 and 21 which are formed at the outer side and extend endwise of the strip. Said offset portions are unequal in size in cross-section and spaced 15 widthwise of said strip. The offset portion 21 is enough larger than the offset portion 20 not only to cover the smaller offset portion 20 but to space the larger offset portion 21 at opposite sides of and from said smaller offset portion when the strip 12 has been 20 spirally wound around the spring as will hereinafter appear. Preferably the smaller offset portion 20 terminates in one of the substantially parallel longitudinal edges of 25 the strip 12 and the larger offset portion 21 is somewhat spaced from the other of said edges. Preferably the end portion 22 of the strip 12 (see Fig. 1) is gradually reduced in width in the direction of the outer extremity of said end portion and 30 toward the smaller offset portion 20 which extends to said extremity, so as to form an edge 23 extending diagonally of the strip from said extremity to the adjacent end of 35 the larger offset portion 21 and so that said larger offset portion is spaced, at its end which terminates in said edge 23, a suitable distance from said extremity in the direction of the other end portion of said strip.
- 40 Preferably the end portion 25 of the strip 12 (see Fig. 1) is reduced in width in the direction of the outer extremity of said end portion and toward the larger offset portion 21 which extends to said extremity, so as 45 to form an edge 26 extending diagonally of the strip from said extremity to the adjacent end of the smaller offset portion 20.
- The dimensions of the end portion 22 50 of the strip 12 are such that, upon applying the outer end of said end portion of said strip to the top of the spring at a point adjacent the eye or member 18 of the spring, as shown in Fig. 5, the diagonal edge 23 of said end portion of said strip has the part 55 thereof which extends along the outer end of said end portion of said strip substantially parallel with said eye or member 18 and, by wrapping said end portion of said strip around the spring the larger offset portion 21 has its end which terminates 60 in said edge 23 brought into such relation to the adjacent end of the smaller offset portion 20 that said end of said smaller offset portion 20 underlies said end of the larger offset portion 21, as shown in Fig. 65

5, and said ends of said offset portions extend diagonally of the spring and are arranged as required to permit and facilitate winding of the strip 12 spirally around the spring in the direction of the thickest portion of the spring.

The spirally wound strip and both of its offset portions 20 and 21 extend several times completely around the spring, and the smaller offset portion 20 of the spirally wound strip is substantially completely covered by or housed in the larger offset portion 21. Preferably the spirally wound strip and its offset portions 20 and 21 extend at least once completely around the spring in every three inches of the length of the casing comprising said strip, and the larger offset portion 21 measures enough more in internal width than the external width of the smaller offset portion 20 to render the spirally wound strip, and consequently the casing comprising said strip, extensible and contractible endwise of the spring so as to permit the desired expansion or contraction of said casing endwise of the spring as may be required during the flexing of the spring. Preferably the smaller offset portion 20 of the spirally wound strip has such dimensions in cross-section in relation to the larger offset portion 21 of said strip that, as shown in Figs. 6, 8 and 9, opposite side portions of said larger offset portion not only extend opposite but are materially spaced from opposite sides respectively of the smaller offset portion 20 when said smaller offset portion is substantially central widthwise of the larger offset portion.

By the construction hereinbefore described it will be observed that the spirally wound strip has one end portion thereof adjacent the movable or free end of the spring and is wound spirally around the spring in the direction of the thickest portion of the spring, and the other end portion of the spirally wound strip terminates adjacent the axle-overlapping or thickest portion of the spring and (see Figs. 3, 7 and 9) extends into close proximity to the adjacent edge of the top plate 15 of the hereinbefore mentioned clip, and said spirally wound strip is shown held at its last-mentioned end portion against unwinding by a sheet-metal strap 28 which surrounds the enclosure formed by said strip and is arranged in close proximity to said clip.

Preferably the strip 12 has its end portion 25 long enough to permit such trimming and contouring of said end portion of said strip, upon winding said strip on the spring, as required not only to form a flange 29 which (see Figs. 3 and 7) projects downwardly from the enclosure formed by the spirally wound strip and is interposed, at the bottom of said enclosure, between the strap 28 and the spring-supporting member

13, but to form a flange 30 which (see Figs. 3, 7 and 9) projects outwardly from said enclosure and is interposed, at the top of said enclosure, between said strap and the adjacent edge of the clip-plate 15.

It will be observed that the strap 28, although it extends over an adjacent part of the larger offset portion 21 of the spirally wound strip as shown in Fig. 7, is confined 10 between another part of said offset portion and the top flange 30 as shown in Figs. 3 and 9, so that the last-mentioned part of said offset portion is arranged to prevent displacement of said strap endwise of the 15 spring-surrounding casing in the direction of the eye or member 18 of the spring, and the flanges 29 and 30 are arranged to prevent displacement of said strap in the opposite direction. Preferably the strap 28 tightly 20 embraces the enclosure formed by the spirally wound strip and (see Fig. 7) has its end portions 31 and 32 arranged at the bottom of and under said enclosure. The end portion 32 of said strap has a slot 33 extending transversely of the strap, and the other end portion 31 of the strap overlaps the inner side of the slotted end portion 32 from the free extremity of said slotted end portion to said slot and extends from said side of 25 said slotted end portion through said slot and is bent, as at 34, against the outer side of said slotted end portion and overlaps the transverse edge of said slotted end portion, as at 35.

35 Under the spring, at a short distance from the eye or member 18 of the spring (see Figs. 6 and 8), is a rectangular metal plate 36 which is arranged at the bottom and extends transversely of the spring-surrounding casing comprising the spirally wound strip and has a central hole 37 extending through the plate and a downwardly projecting annular flange 38 extending circumferentially of said hole and engaging but not projecting below 40 a hole 39 formed in the bottom of said casing. The tubular body 40 of a lubricant-supplying cup, arranged in the main externally of said casing, has its inner end portion screw-threaded externally and threaded 45 at the hole 37 into the plate 36, and said body has an external annular shoulder 41 abutting against the outer side of the bottom of said casing, and said bottom is clamped by and between said shoulder and 50 said plate. The plate 36 and the member 40 are applied during or preparatory to the formation of said casing. Preferably the plate 36 has its transverse or end edges in close proximity to and facing the sides of 55 said casing so that said plate is held against displacement circumferentially of the inner end of the body 40. Said body 40 is screw-threaded internally, and a correspondingly externally threaded plug 42 is screwed into 60 and therefore removable from said body.

Obviously, when the body 40 contains grease or lubricant between the inner end of the plug 42 and the inner end of said body, rotation of said plug in the direction required to shift the plug inwardly results in the discharge of lubricant from the inner end of 70 said body.

By the construction hereinbefore described it will be observed that the member 40 constitutes the lubricant-inlet of the spring-surrounding casing, and that the offset portions 20 and 21 of the spirally wound strip form a spirally extending outward enlargement of said casing and extend spirally around the spring and substantially from 75 end to end of the said strip and thereby materially enlarge the lubricant-containing capacity of said casing so that adequate lubrication of the leaves of the spring is facilitated and insured.

What I claim is—

1. The combination, with a laminated spring which has an end free to move and is reduced in thickness toward said end and adapted to be supported at a point spaced from said end, of a casing comprising a flexible strip which is wound around the spring in the direction of the thickest portion of the spring and held against unwinding and has two spaced outwardly projecting portions 80 extending endwise of the strip, one of said projecting portions of the spirally wound strip being contoured in cross-section and arranged as required to form a cover or housing for the other of said projecting portions and having the dimensions required to permit and facilitate flexing of the casing and spring.

2. The combination, with a laminated spring which has an end free to move and is reduced in thickness toward said end and adapted to be supported at a point spaced from said end, of a flexible sheet-metal strip which is wound around the spring in the direction of the thickest portion of the spring 85 and has two spaced outwardly projecting portions extending endwise of the strip, one of said projecting portions of the spirally wound strip being contoured in cross-section and arranged as required to form a cover or housing for the other of said projecting portions and having the dimensions required to render the spirally wound strip 90 extensible and contractible endwise of the spring, and said spirally wound strip being held, adjacent the thickest portion of the spring, against unwinding.

3. The combination, with a laminated spring which has an end free to move and is adapted to be supported at a point spaced from said end, of a flexible strip which has one end portion thereof adjacent said end of the spring and is wound around the spring in the direction of the aforesaid point and has two spaced outwardly projecting offset 125

- portions which extend endwise of the strip and spirally around the spring and are unequal in size in cross-section, the larger offset portion of the spirally wound strip being 5 arranged externally of and forming a cover for the smaller offset portion of said strip and having the dimensions required to render the spirally wound strip extensible and contractible endwise of the spring, and said 10 spirally wound strip being held at its other end portion against unwinding.
4. The combination, with a laminated spring which has an end free to move and is adapted to be supported at a point spaced 15 from said end, of a flexible strip which has one end portion thereof adjacent said end of the spring and is wound from its said end portion spirally around the spring in the direction of the aforesaid point and has two spaced outwardly projecting portions extending endwise of the strip, one of said projecting portions of the spirally wound strip extending opposite the sides of and farther outwardly than the other projecting 20 portion and being contoured in cross-section and arranged as required to form a cover for the last-mentioned projecting portion and having the dimensions required to render the spirally wound strip extensible and 25 contractible endwise of the spring, and said spirally wound strip being held at its other end portion against unwinding.
5. The combination, with a laminated spring reduced in thickness toward one end 30 and adapted to be supported at its thickest portion, of a flexible strip which has one end portion thereof adjacent said end of the spring and is wound spirally around the spring in the direction of the thickest portion of the spring and has two spaced outwardly projecting portions extending endwise of said strip, one of said projecting portions of the spirally wound strip being contoured in cross-section and arranged as required to form a cover for the other of said 35 projecting portions and having the dimensions required to render the spirally wound strip extensible and contractible endwise of the spring, and means arranged adjacent the thickest portion of the spring and holding the spirally wound strip, at the other end portion of said strip, against unwinding.
6. The combination, with a laminated spring reduced in thickness toward one end 40 and adapted to be supported at its thickest portion, of a flexible strip which has one end portion thereof adjacent said end of the spring and is wound spirally around the spring in the direction of the thickest portion of the spring and has two spaced outwardly projecting portions extending endwise of said strip, one of said projecting portions of the spirally wound strip extending opposite the sides of and farther outwardly 45 than the other projecting portion and be-
- ing contoured in cross-section and arranged as required to form a cover for the last-mentioned projecting portion and having the dimensions required to render the spirally wound strip extensible and contractible 70 endwise of the spring, and a strap arranged adjacent the thickest portion of the spring and extending around the enclosure formed by the spirally wound strip and holding said spirally wound strip, at the other end portion of said strip, against unwinding.
7. The combination, with a laminated spring reduced in thickness toward one end and adapted to be supported adjacent its thickest portion, of a flexible strip which has one end portion thereof adjacent said end of the spring and is wound spirally around the spring in the direction of the thickest portion of and forms an enclosure 80 for the spring, and a sheet-metal strap arranged adjacent the last-mentioned portion of the spring and extending around said enclosure, one end portion of said strap having a slot extending transversely of the strap, the other end portion of the strap overlapping the inner side of the slotted end portion of the strap between the slot and the free extremity of said slotted end portion and extending from said side of said slotted end portion through the slot and being bent 85 against the outer side of said slotted end portion.
8. The combination, with a laminated spring reduced in thickness toward one end and adapted to be supported at its thickest 90 portion, of a flexible strip which has one end portion thereof adjacent said end of the spring and is wound spirally around the spring in the direction of the thickest portion of and forms an enclosure for the spring 95 and has two spaced outwardly projecting offset portions which are formed at the outer side of said strip and unequal in size in cross-section and extend endwise of the strip, and a strap arranged adjacent the last-mentioned portion of the spring and extending around said enclosure, the larger offset portion of the spirally wound strip being arranged externally of and forming a cover 100 for the smaller offset portion of said strip, and the aforesaid strap being held against movement endwise of the aforesaid enclosure.
9. The combination, with a laminated spring reduced in thickness toward one end 105 and adapted to be supported adjacent its thickest portion, of a flexible strip which has one end portion thereof adjacent said end of the spring and is wound spirally around the spring in the direction of the thickest portion of the spring and has two spaced outwardly projecting offset portions which are formed at the outer side of said strip and unequal in size in cross-section and extend 110 endwise of the strip, the larger offset portion of the spirally wound strip being arranged externally of and forming a cover for the smaller offset portion of said strip, and the aforesaid strap being held against movement endwise of the aforesaid enclosure.

tion of the spirally wound strip being arranged externally of and forming a cover for the smaller offset portion of the strip, both of said offset portions being contoured in cross-section and arranged as required to form a spirally extending lubricant-receiving enlargement of the casing, and the spirally wound strip being held, at its other end portion, against unwinding.

10. The combination, with a laminated spring reduced in thickness toward one end and adapted to be supported adjacent its thickest portion, of a casing comprising a flexible strip which has one end portion thereof adjacent said end of the spring and is wound spirally around the spring in the direction of the thickest portion of the spring and held against unwinding and has two spaced outwardly projecting offset portions which are formed at the outer side of said strip and unequal in size in cross-section and extend endwise of the strip, the larger offset portion of the spirally wound strip being arranged externally of and housing the smaller offset portion of the strip and forming a spirally extending lubricant-receiving enlargement of the casing.

11. The combination, with a laminated spring reduced in thickness toward one end and adapted to be supported adjacent its thickest portion, of a casing comprising a flexible strip which is wound spirally around the spring in the direction of the thickest portion of the spring and held against un-

winding and has two spaced outwardly projecting portions both of which extend endwise of the strip and one of which forms a cover for the other and has the dimensions required to render the spirally wound strip extensible and contractible endwise of the spring, a plate arranged internally of and extending transversely of the casing and having at each end a transverse edge in close proximity to and facing the adjacent side of the casing and also having a hole which extends through the plate, and a lubricant-supplying cup having a body which is arranged in the main externally of the casing and secured at said hole to said plate and has an annular shoulder externally of the casing, the casing having a portion extending between said shoulder and said plate, and said portion of the casing being clamped by and between said plate and said shoulder.

12. A spring casing comprising a continuous ribbon formed about spring laminations and convolutions extending the full length of the spring, said ribbon having beaded edges, the bead on one edge being larger than the bead on the other edge, whereby an overlapping inter-engagement of each convolution may be obtained with adjacent convolutions, and thereby permit relative movement of the respective convolutions.

In testimony whereof, I sign the foregoing specification, this 4th day of March, 1922.

JOHN ZULICH.
